SMOKE ELIMINATING APPARATUS

Conway Pierce, Detroit, Mich.

Application June 18, 1947, Serial No. 755,296

16 Claims. (Cl. 236—15)

1

This invention relates to apparatus for eliminating or substantially reducing the production of smoke in fuel burning equipment, and refers more particularly to apparatus of the above type wherein fluid is introduced to the combustion zone of the equipment to improve combustion in the latter zone.

One of the objects of this invention is to improve generally apparatus of the above type by providing relatively simple smoke detector means for automatically controlling the fluid supply means in response to the density of the smoke discharged from the fuel burning equipment.

Another feature of this invention is to incorporate in the control apparatus a timing device which is rendered operative by the smoke detector means to connect the fluid supply means to the combustion zone of the fuel burning equipment and maintains this connection for a predetermined period of time, regardless of the condition of the smoke detector means. This arrangement assures effective elimination of the smoke and minimizes repeated starting and stopping of the apparatus.

Still another feature of this invention is to provide an arrangement wherein the fluid supplied to the combustion zone may be supplied from areas within the combustion chamber or may be supplied from the atmosphere exteriorly of the chamber, or in some instances, may be taken from both places. By supplying air to the combustion zone which is collected from areas within the chamber, a minimum loss of heat results because the amount of air to the furnace is not thereby increased with a consequent increase of heat losses in the exit flue gases.

A further object of this invention is to provide smoke abatement apparatus having two or more fluid supply devices, and having means for successively operating the devices in response to the production of smoke in the combustion chamber.

A still further object of this invention is to provide apparatus of the type set forth in the preceding paragraph having means for delaying the operation of the second device for a predetermined period of time after the first device is started.

The foregoing as well as other objects will be made more apparent as this description proceeds, especially when considered in connection with the accompanying drawings, wherein:

Figure 1 is a diagrammatic sectional elevational view showing fuel burning equipment embodying smoke abatement apparatus constructed in accordance with this invention;

Figure 2 is a wiring diagram of the arrangement shown in Figure 1;

Figure 3 is a diagrammatic sectional elevational view of a modified construction;

Figure 4 is a wiring diagram for the arrangement shown in Figure 3;

2

Figure 5 is a diagrammatic view of another embodiment of the invention;

Figure 6 is a diagrammatic sectional elevational view of a further embodiment of this invention; and

Figure 7 is a wiring diagram for the arrangement shown in Figure 6.

Each of the several embodiments of this invention about to be described are applicable to practically any type of fuel burning equipment in which improper combustion results in the production of smoke. Also provision is made in each of the several modifications illustrated herein for introducing fluid into the combustion zone of the equipment in response to the density of the smoke generated by the equipment. The introduction of fluid to the combustion zone of the fuel burning equipment creates a turbulence in the combustion chamber and supplies additional air to the region in which combustion originates. This additional air materially aids combustion and is supplied in sufficient quantities to assure substantially complete burning of the smoke or unburned gases in the combustion chamber, so that very little or no perceptible amount of smoke or unburned gases escape from the combustion chamber through the flue usually provided for this purpose.

As will be more fully hereinafter set forth, the fluid or air may be supplied to the combustion zone from the atmosphere exteriorly of the chamber, or may be supplied to the combustion zone from the remote areas in the chamber proper. In fact the supplemental air may, under certain conditions, be taken both from the atmosphere exteriorly of the chamber and from points within the chamber. The advantage of supplying the supplemental air from a region within the chamber is that the quantity of excess air is not increased by the process and the heat losses carried away to the flue in the form of sensible heat is kept at a minimum.

With the above in view, reference is now made more in detail to the embodiment shown in Figures 1 and 2 of the drawings. Referring first to Figure 1 of the drawings, it will be noted that the reference numeral 10 indicates a conventional type of coal burning furnace having a combustion chamber 11 and having a combustion zone indicated generally by the reference numeral 12. In accordance with orthodox practice, the products of combustion are discharged from the chamber 11 through a flue 13 extending from the furnace 10 in communication with the chamber 11. In the normal operation of a furnace of the above general type, all of the gases are not thoroughly burned due to the presence of insufficient air in the combustion zone 12, and these gases are released through the flue 13 in the form of smoke, which for the purpose of this description is considered the gaseous products of combustion made visible by small particles of car-

bon suspended therein. The density of the smoke passing upwardly through the flue depends upon the number of particles of carbon suspended therein, which in turn depends on the efficiency at which combustion takes place in the zone 12. The particles of carbon suspended in the smoke or products of combustion eventually settle out in the form of soot, and this, of course, is very objectionable.

In order to increase the efficiency of combustion in the zone 12 of the chamber 11 sufficiently to avoid the production of smoke, provision is made herein for introducing air and steam into the zone 12. In the present instance air is introduced into the chamber 11 from the atmosphere exteriorly of the latter through a tube 14 extending through one side wall of the furnace 10 and positioned with the delivery end directly opposite the zone 12. Air is induced to flow through the tube 14 into the combustion chamber 11 by discharging a stream of steam through the tube 14. The steam is discharged into the entrant end of the tube by a jet 15 spaced axially outwardly from the supply end of the tube a sufficient distance to enable the entrance of air into the tube and connected to a suitable source of supply (not shown) by a conduit 16. The flow of steam from the source of supply to the jet is controlled by a conventional two-way valve 17 suitably supported in the conduit 16 between the jet 15 and the source of supply.

The valve 17 is automatically operated in response to the density of the smoke passing through the flue 13. The means for accomplishing the above result comprises a source of illumination 18 and a light sensitive unit 19, respectively suitably supported at opposite sides of the flue. The source of illumination 18 is electrically connected to a source of electric energy 20 by a circuit 21 having a manually operable switch 22 therein. The light sensitive unit 19 may be any one of a number of orthodox units available to the trade and need not be described in detail herein. It will suffice to point out that the unit 19 comprises a photoelectric cell 23 and a relay switch 24.

The above arrangement is such that the photoelectric cell 23 is energized by rays of light projected across the flue 13 by the illuminating device 18, and thereby maintains the relay switch 24 in its open position. On the other hand, when the beam of light emitted by the device 18 is interrupted or substantially diminished by the density of the smoke passing through the flue, the photoelectric cell is deenergized, and the relay switch 24 is closed. Referring again to Figure 2 of the drawings, it will be noted that the photoelectric cell is connected to the source 20 of electrical energy by an operating circuit 25 having a manually operable switch 26 therein. In practice the switch 26 is located in close proximity to the switch 22, and both switches are normally closed when the apparatus is in its operative condition.

The operating circuit 25 also includes a solenoid 27 having a coil 28 connected in series in the circuit 25 and having an armature 29 in the coil operatively connected to the valve 17. The valve 17 is normally closed, and is moved to its open position by the armature 29 when the coil 28 of the solenoid is energized by the operating circuit 25.

The operating circuit is controlled by an electrically operated timer 30, which also may be any one of the standard types available to the

trade, and therefore, is not described in detail herein. It will suffice to point out that the timer is of the automatic resetting type having an electric motor 31 for operating the timing means 32 and having a relay switch 33 connected in series in the operating circuit 25. In accordance with conventional practice, the switch 33 is closed by the timer as soon as the motor 31 is operated to start the timing means 32. The means 32 may be previously set in accordance with orthodox practice to correspond to a predetermined time interval. When this time interval expires, operation of the motor 31 is discontinued and the switch 33 is not only opened, but the timing means is automatically reset to its zero or initial starting position.

The timing device briefly described above is energized by a control circuit 34 including the motor 31 of the timing device, and also including the relay switch 24. It follows, therefore, that when the relay switch 24 is closed by the presence of smoke in the flue 13, the motor 31 in the timer is started, and the switch 33 is closed. Closing of the switch 33 in the timer 30 energizes the coil 28 of the solenoid 27 and operates the armature 29 to open the valve 17. As stated above, opening of the valve 17 introduces steam and air into the combustion zone 12 in the chamber 11. The introduction of this fluid into the chamber 11 produces a turbulence in the chamber, so that air from remote areas in the chamber is also circulated through the combustion zone 12. This turbulence also causes the smoke which has accumulated in the chamber 12 to pass or circulate through other parts of the combustion zone where there is sufficient air for burning. The unburned smoke and gases are thereby quickly burned and pass from the furnace as a smokeless product.

When the density of the smoke passing through the flue between the light source 18 and light sensitive unit 19 diminishes to such an extent as to permit the beam of light from the source to again energize the photoelectric cell 23, the switch 24 is opened. At this point it is important to note that the control circuit 34 is so connected with the operating circuit 25 that both the motor 31 and switch 33 are connected in parallel relation with the relay switch 24. Thus the solenoid 27 remains energized or, in other words, the valve 17 remains open until both switches 24 and 33 are opened. Accordingly, should the switch 24 open before the timing means 32 on the timer 30 reaches the preselected setting, the motor 31 continues to operate, and the switch 33 remains closed until the timer completes its cycle of operation. Thus the introduction of fluid into the combustion chamber is continued until the timer relay switch 33 is opened. It follows from the above that the operating circuit is maintained closed by the timer 30 for a predetermined length of time, regardless of the condition of the relay 24, and this is highly desirable in that it prevents constant fluctuation or repeat operation of the apparatus.

The embodiment of the invention shown in Figures 3 and 4 of the drawings differs from the above described arrangement in that a blower 35 is provided for supplying air to the combustion chamber 11. The blower 35 is driven by an electric motor 36 of suitable design and the latter is connected to a power circuit 37 including a switch 38. The switch 38 takes the place of the valve 17 shown in Figure 2 of the drawings, and is automatically operated by the solenoid 27.

The solenoid 27 is operated in response to the density of the smoke passing through the flue 13 by the same circuit arrangement shown in Figure 1. Accordingly corresponding parts of the two embodiments described above are indicated by the same reference numerals.

The timer 33 and associated parts are replaced in the embodiment of the invention shown in Figure 5 of the drawings by a fluid pressure operated timing system designated generally by the numeral 46. This system comprises a number of parts among which are a displacement pump 41, a fluid motor 42, a control valve 43 and a reservoir 44. The pump 41 may be operated by any suitable type of prime mover, and has a piston 45 slidably supported in a cylinder 43 having the end at the pressure side of the piston connected to the reservoir through a check valve 47. The end aforesaid of the pump cylinder also has a fluid connection with the control valve 43 and a check valve 48 is included in the above connection to prevent flow of fluid from the valve to the pump cylinder.

The fluid motor 42 has a piston 49 slidably mounted in a cylinder 50 connected at its upper end to the reservoir by a fluid return conduit 51 and connected at its lower end to the control valve by a conduit 52. The lower end of the cylinder 50 is also connected to the fluid return conduit 51 by a conduit 53 including a metering valve 54. The piston 49 has a mechanical connection with one end of a lever 55 by a rod 56 extending downwardly from the piston 49 through an opening in the lower end of the cylinder 50 and the other end of the lever 55 is pivoted to a suitable fixed support 57. The lever 55 is connected intermediate the ends to a valve 17 identical in purpose to the correspondingly numbered valve in the first embodiment of the invention. The valve 17 is normally urged to its closed position by a coil spring 58 having the lower end bearing on the lever intermediate the ends of the latter and having the upper end engaging an abutment 59 fixed to the upper end of a vertical rod 60. The rod extends axially through the coil spring and is connected to the valve 17. The general arrangement is such that the coil spring 58 tends to maintain related positions between the lever 55, rod 60 and valve 17, such that when the lever 55 is down, the valve 17 is closed by the spring 58.

The valve 43 is normally held in its closed position or in a position wherein the portion of the power cylinder 50 below the piston 49 is closed to the discharge side of the pump cylinder 41. The valve 43 is operated by a solenoid 27 identical to the correspondingly numbered solenoid in the operating circuit 25 of the first embodiment of this invention. The same type of operating circuit is provided in Figure 5 of the drawings and is automatically controlled in response to the density of the smoke passing through the flue by the same instrumentalities described in connection with the arrangement disclosed in Figures 1 and 2 of the drawings.

In operation when the solenoid 27 is energized the valve 43 is opened permitting fluid under pressure to flow from the discharge side of the pump 41 to the lower end of the power cylinder 50 below the piston 49. As the piston 49 is moved upwardly in the cylinder 50 by the pressure of the fluid acting on the bottom surface of the piston, the free end of the lever 55 is swung upwardly compressing the spring 58 and thereby open-

ing the valve 17 to admit steam and air into the combustion chamber 11 through the tubes 14.

Assuming now that the smoke condition in the combustion chamber 11 has been relieved or eliminated, and that the light sensitive cell controlled relay 24 is again opened, it will be noted that the solenoid 27 is deenergized and the valve 43 is again closed. However, the valve 17 is prevented from closing by the rod 60 and remains open until the pressure in the cylinder 50 below the piston 49 drops sufficiently to enable downward movement of the piston by the spring 58. In the present instance the rate at which fluid escapes from the lower end of the cylinder 50 is regulated by the needle valve 54 and, as a consequence, any desired lag between opening of the relay 24 and closing of the valve 17 may be provided. Of course if the relay 24 again closes before the valve 17 is closed, the valve 43 opens, and closing of the valve 17 is further delayed. Thus effective elimination of the smoke in the combustion chamber 11 is assured, and the objectionable fluctuating action of the control mechanism is avoided.

In Figures 6 and 7 of the drawings, I have shown a dual stage smoke abatement system in connection with a power boiler and furnace equipped with an overfeed coal stoker of the chain grate type. This type of equipment is well known in the art, and need not be described in detail. For the purpose of this description, it will suffice to point out that this furnace is also provided with a combustion zone 12 in the chamber 11 and with a flue 13 through which the products of combustion are discharged.

Referring now more in detail to Figure 7 of the drawings, it will be noted that the reference numeral 60 indicates the first stage of the smoke abatement apparatus, and the numeral 61 designates the second stage. The operation of the two stages is controlled by a common light source 18 and a common light sensitive unit 19 positioned at opposite sides of the path of the products of combustion flowing from the combustion chamber 11 through the flue 13. These instrumentalities are the same as those previously described in connection with the above modifications of this invention, and operate in an identical manner.

Actually, the stage 60 corresponds to the embodiment shown in Figures 3 and 4 of the drawings, and similar parts are indicated by the same reference characters. However, in Figure 6 of the drawings, the intake side of the blower 35 is connected to a conduit 62 which extends into the boiler setting and is positioned to draw gas from the last pass 63 of the boiler. The discharge side of the blower is connected to delivery tubes 64 by a supply conduit 65 and these tubes are positioned to discharge the gases into the combustion zone 12 of the furnace. As pointed out in connection with the modification shown in Figures 3 and 4 of the drawings, the blower 35 is operated by an electric motor 36 connected in an electric supply circuit 37 and controlled by a switch 38 in said circuit. The switch 38 is operated by a solenoid 27 and the latter in turn is operated in response to the density of the smoke passing upwardly through the flue 13. As further pointed out in the description of the first embodiment of this invention, the coil 28 of the solenoid 27 is electrically connected in an operating circuit 25 including the switch 33 of the timer 30, and the motor 36 for the timer is electrically connected in both the operating circuit 25 and control circuit 34. The arrangement

is such that should the relay switch 24 open prior to completion of the operation of the timer, the latter continues to operate under power received from the operating circuit 25.

The second stage of the smoke abatement system comprises a plurality of jets 66 corresponding to the jets 15 and adapted to inject air and steam into the combustion chamber through one or more sides of the furnace in the same manner described in connection with Figures 1 and 2 of the drawings. The flow of steam to the jets 66 is controlled by a valve 17 and the latter is operated by a solenoid 27' identical to the solenoid 27. The coil 28' of the solenoid 27' is connected in an operating circuit 25' in parallel with the coil 28 of the solenoid 27 and is operated by the relay 24 through a second timer 33' identical to the timer 30. The switch 33' of the timer 30' is electrically connected in the operating circuit 25' in parallel with the timer switch 33, and the motor 31' for the second timer 30' is connected in the operating and control circuits so as to continue operation of the timer until it completes its cycle, regardless of the condition of the relay switch 24.

As shown in Figure 7 of the drawings, a time delay relay switch 67 is connected in series with the timer motor 31', and a relay switch 68 is connected in series with the timer motor 31. The switch 68 is normally closed and the actuating coil of this switch is connected in series with the switch 33' of the timer 30', so that when the switch 33' is closed to energize the solenoid 27', the switch 68 is opened. The time delay switch 67 may be of any suitable design available to the trade, and the actuating coil thereof is shown in Figure 7 as connected in parallel with the timer 30'. As a result, the coil for the switch 67 is energized as soon as the operating circuit 25 is closed by the timer switch 33. However, the closing of the switch 67 is delayed for some time, as will be presently described.

In operation of the modified construction shown in Figures 6 and 7 of the drawings, it will be noted that when the density of the smoke passing through the flue 13 exceeds a value sufficient to interrupt the light beam directed by the source 18 toward the light sensitive unit 19, the relay switch 24 closes and starts the timer 30. As a result the switch 33 closes the operating circuit 25, and the switch 38 is closed by the solenoid 27 to operate the blower 35. The blower draws heated gas from the last pass of the boiler and delivers it to the combustion zone 12 of the chamber 11 to improve the efficiency of the combustion taking place in this zone.

In most instances the above procedure will eliminate smoke production with negligible heat loss. However, in some instances, the production of smoke in the furnace may be so severe that it cannot be eliminated by the above operation. In such cases the time delay switch 67 closes and starts operation of the timer 30', which like the timer 30, has been preset to operate for a preselected period of time. The switch 33', of course, closes the circuit 25' to the solenoid 27' and causes the latter to open the valve 17. Thus steam and air from the outside of the furnace are supplied to the combustion zone 12 to supplement the gases supplied by the blower and combustion in the zone 12 is immediately improved. Attention is called to the fact that closing of the switch 33' also energizes the relay coil for the switch 68 and opens the latter to discontinue operation of the motor 31 for the timer

30, so that the blower will continue to operate during the period the second stage 61 of the system is in operation.

When the timer 30' completes its operation and the timing means is reset to its zero or initial starting position, the switch 33' is operated to open the operating circuit 25'. As a result the solenoid 27' is deenergized and the valve 17 is again closed. Opening of the operating circuit 25' by the timer switch 33' also deenergizes the coil of the relay switch 68 and permits the latter to again close. This enables the timer motor 31 to continue its operation until the pre-selected timing period is expired, whereupon the switch 33 is opened and operation of the blower 35 is discontinued. Opening of the switch 24 also serves to deenergize the coil for the time delay relay switch 67 and permits the latter to open, so that the timer 30' is again disconnected from the control circuit 34 of the system. Thus both stages of the system are again ready to operate on demand from the smoke detector and the cycle repeats for another preselected period of time when smoke is again detected.

The second stage 61 will not start operating until the first stage 60 is operated for a length of time determined by the time delay switch 67. Therefore, the second stage 61 may be considered as an emergency system which is called upon to afford protection only in severe cases, or in the event of failure of the first stage.

What I claim as my invention is:

1. Apparatus for substantially eliminating the production of smoke resulting from improper combustion of a fuel in a chamber having an outlet through which the products of combustion pass, said apparatus comprising means for supplying a smoke reducing fluid to the combustion zone in the chamber, an electric circuit having a switch connected in series in said circuit, a solenoid for operating the fluid supplying means and having a coil connected in series in said circuit, means for opening and closing the switch including an electrically operated timer of the automatic resetting type having provision for delaying opening of the switch for a predetermined time, a control circuit for the timer, and means controlled by the density of the smoke discharged from the combustion chamber for closing the control circuit upon an increase in the smoke density above a predetermined value and for opening the control circuit upon a decrease in smoke density below said predetermined value.

2. Apparatus for substantially eliminating the production of smoke resulting from improper combustion of a fuel in a chamber having an outlet through which the products of combustion pass, said apparatus comprising means for supplying a fluid to the combustion zone in the chamber, electrically operated means for controlling the operation of the fluid supplying means and including an electric operating circuit having a switch therein, an electric control circuit having means for closing said switch, a switch in the control circuit controlled by the density of the smoke discharged from the chamber for closing the switch in the control circuit upon an increase in the smoke density at the outlet above a predetermined value and for opening the switch in the control circuit at the outlet upon a decrease in the smoke density below said predetermined value, and means for delaying opening of the switch in the operating circuit for a predetermined period of time.

3. Apparatus for substantially eliminating the production of smoke resulting from improper combustion of a fuel in a chamber having an outlet through which the products of combustion pass, said apparatus comprising an electric control circuit having a relay, means also in the control circuit responsive to an increase in smoke density at the outlet above a predetermined value to close the relay and responsive to a decrease in smoke density at the outlet below said predetermined value to open said relay, means for supplying a smoke reducing fluid to the combustion zone in the chamber in response to closing of the relay and a timer rendered operative by the closing of the relay and having means for continuing the supply of fluid to the chamber for a preselected period of time independently of the operation of said relay.

4. Apparatus for substantially eliminating the production of smoke resulting from improper combustion of a fuel in a chamber having an outlet through which the products of combustion pass, said apparatus comprising an electric control circuit having a switch, means also in the control circuit responsive to an increase in smoke density at the outlet above a predetermined value to close the switch and responsive to a decrease in smoke density at the outlet below said predetermined value to open the switch, means for supplying fluid to the combustion zone of the chamber including an operating electric circuit, a switch in the operating circuit shunting the switch in the control circuit, and a timer for operating the second named switch including electrically operated mechanism connected in the control circuit.

5. Apparatus for substantially eliminating the production of smoke resulting from improper combustion of a fuel in a chamber having an outlet through which the products of combustion pass, said apparatus comprising an electric control circuit having a relay movable to its open and closed positions in response to the density of the products of combustion discharged from the chamber, an electrically operated blower having the discharge side communicating with the chamber and included in an electric supply circuit having a switch, an operating electric circuit including means for operating the switch in the supply circuit, and a timer having a switch shunting the switch in the control circuit and having mechanism for operating the timer switch connected in the control circuit.

6. Apparatus for substantially eliminating the production of smoke resulting from improper combustion of a fuel in a chamber having an outlet through which the products of combustion pass, said apparatus comprising an electric control circuit having a relay movable to its open and closed positions in response to the density of the products of combustion discharged from the chamber, valve controlled means for supplying fluid to the combustion zone in the chamber, means for opening and closing the valve in response to the operation of the relay, and fluid pressure operated means for delaying closing of said valve for a predetermined period of time regardless of the condition of said relay.

7. Apparatus for substantially eliminating the production of smoke resulting from improper combustion of a fuel in a chamber having an outlet through which the products of combustion pass, said apparatus comprising an electric control circuit having a relay, means also in the control circuit responsive to an increase in

the smoke density at the outlet above a predetermined value to close the relay and responsive to a decrease in smoke density at the outlet below said predetermined value to open the relay, means for supplying fluid to the combustion zone of the chamber, means for operating the supply means in response to closing of the relay including an operating circuit having a solenoid, a switch connected in the operating circuit in series with the solenoid and shunting the switch in the control circuit, and an electrically operated timer connected in the control circuit for closing and opening the switch in said operating circuit.

8. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, means for successively closing the switches in response to closing of the relay switch, and means for delaying closing of the second switch for a predetermined period of time after closing of the first switch.

9. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, a timer for closing the first switch in response to closing of the relay switch and for maintaining said first switch closed for a predetermined period of time, a second timer for closing the second switch, and time delay means in response to closing of the relay switch for initiating the operating of the second timer.

10. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, a timer for closing the first switch in response to closing of the relay switch and for maintaining said first switch closed for a predetermined period of time, a second timer for closing the second switch in response to closing of the relay switch and for maintaining the second switch closed for a predetermined period of time, and means for de-

laying operation of the second timer to close the second switch for a predetermined period of time after closing of the first switch.

11. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, a timer for closing the first switch in response to closing of the relay switch and for maintaining said first switch closed for a predetermined period of time, a second timer for closing the second switch in response to closing of the relay switch and for maintaining the second switch closed for a predetermined period of time, means for delaying operation of the second timer for a predetermined length of time, and means for interrupting the timing cycle of the first timer in response to operation of the second timer to close the second switch.

12. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, a timer for closing the first switch in response to closing of the relay switch and for maintaining said first switch closed for a predetermined period of time, a second timer for closing the second switch in response to closing of the relay switch and for maintaining the second switch closed for a predetermined period of time, means for delaying operation of the second timer to close the second switch for a predetermined period of time after closing of the first switch, and means for interrupting the timing cycle of the first timer in response to operation of the second timer.

13. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, means for supplying a fluid to the combustion zone in the chamber including an operating circuit having two solenoids connected in parallel in the operating circuit, first and second switches in the operating circuit for respectively controlling the solenoids, a timer for closing the first switch in response to closing of the relay switch and for maintaining said first switch closed for a predetermined period of time, a second timer for closing the second switch in response to closing of the relay switch

and for maintaining the second switch closed for a predetermined period of time, means for delaying operation of the second timer to close the second switch for a predetermined period of time after closing of the first switch, and a normally closed relay switch for also controlling the operation of the first timer and connected in series with the second switch for successively stopping and starting the first timer upon closing and opening the second switch.

14. Apparatus for substantially eliminating the production of smoke resulting from improper combustion of a fuel in a chamber having an outlet through which the products of combustion pass, said apparatus comprising an electric control circuit having a relay switch movable to its open and closed positions in response to the density of the products of combustion discharged from the combustion zone, first and second devices for independently supplying fluid to the combustion zone, and means responsive to closing of the relay switch for successively operating said devices.

15. Apparatus for substantially eliminating the production of smoke resulting from improper combustion of a fuel in a chamber having an outlet through which the products of combustion pass, said apparatus comprising electric control circuit having a relay switch movable to its open and closed positions in response to the density of the products of combustion discharged from the combustion zone, first and second devices for independently supplying fluid to the combustion zone, and means for delaying the operation of the second device for a predetermined period of time after the operation of the first device.

16. Apparatus for substantially eliminating the production of smoke resulting from improper combustion of a fuel in a chamber having an outlet through which the products of combustion pass, said apparatus comprising means for supplying a smoke reducing fluid to the combustion zone in the chamber, an electric operating circuit having a switch connected in series therein, means in said circuit for operating the fluid supply means and controlled by said switch, a timer for opening and closing said switch, a control circuit having means for operating the timer, a switch in the control circuit for opening and closing the control circuit, and means controlled by the density of the smoke passing through the outlet for closing the switch in the control circuit upon an increase in smoke density above a predetermined value and for opening the switch in the control circuit upon a decrease in the smoke density below said predetermined value.
